DESIGN FOR A HANDLE BAIL FOR A SUCTION CLEANER OR SIMILAR ARTICLE

Henry Dreyfuss, New York, N. Y., assignor to The Hoover Company, North Canton, Ohio, a corporation of Ohio

Application November 7, 1935, Serial No. 59,429

Term of patent 14 years

To all whom it may concern:

Be it known that I, Henry Dreyfuss, a citizen of the United States, residing at New York city, in the county of New York and State of New York, have invented a new, original, and ornamental Design for a Handle Bail for a Suction Cleaner or Similar Article, of which the following is a specification, reference being had to the accompanying drawing, forming a part thereof.

In the drawing:

Figure 1 is a top view of the handle bail for a suction cleaner or similar article, showing my new design; and

Figure 2 is a front elevation of the handle bail; and

Figure 3 is a side view of the bail.

I claim:

The ornamental design for a handle bail for a suction cleaner or similar article, as shown.

HENRY DREYFUSS.
